UNITED STATES PATENT OFFICE.

CECILE E. CROSWHITE, OF KANSAS CITY, MISSOURI.

VANITY CASE.

Application filed May 22, 1925. Serial No. 32,038.

To all whom it may concern:

Be it known that I, CECILE E. CROSWHITE, a citizen of the United States, residing at Kansas City, in the county of Jackson and 5 State of Missouri, have invented a certain new and useful Improvement in Vanity Cases, of which the following is a specification.

My invention relates to improvements in 10 vanity cases.

One of the objects of my invention is to provide, in a vanity case, novel powder containing means by which powder in said containing means is held from being accidentally spilled therefrom when the case is being used.

My invention provides further, in a vanity case, a novel device for releasably holding a comb and also securing a mirror in the 20 case.

Still another object of my invention is to provide a novel vanity case, which is simple, ornamental, easily operated, durable, and not liable to get out of order.

25 The novel features of my invention are hereinafter fully described and claimed.

In the accompanying drawing, which illustrates the preferred embodiment of my invention.

30 Fig. 1 is a perspective view, reduced, of my improved vanity case, shown closed.

Fig. 2 is an enlarged vertical sectional view of the same.

Fig. 3 is a horizontal section, also enlarged, on the line 3—3 of Fig. 4, the case being shown in an open position.

Fig. 4 is a section on the line 4—4 of Fig. 3.

40 Similar reference characters designate similar parts in the different views.

My improved vanity case is provided with two preferably rectangular members consisting of two boxes 1 and 2, which are connected together by means of a hinge 3, provided with a pintle 4, disposed parallel with and adjacent to the adjacent edges of the boxes 1 and 2.

45 In the box 1, is provided a partition plate 5, which is disposed parallel with and spaced apart from the bottom of the box 1, so as to form a chamber adapted to receive powder 6 and a powder puff 7. One edge of the partition 5 is spaced apart from the wall 8 of the chamber, so as to form an opening

9 for the insertion into said chamber of the 55 powder 6 and the powder puff 7.

Hinged to the pintle 4 is a cover 10, which is adapted to be swung from the open position shown in Figs. 3 and 4, to a closed position shown in Fig. 2, in which it will lie 60 against the partition plate 5, and will cover the chamber which is adapted to contain the powder 6 and the puff 7.

The plate 10 may form the bottom of a box having two chambers 11 and 12, 65 adapted to receive desired articles and adapted to be closed by a hinged lid 13 provided on its outer side with a resilient plate 14 adapted to serve with the lid 13 70 as a card receiver, one end of the plate 14 being free and adapted to bear against the lid 13, and the other end being rigidly attached to the lid.

15 designates a mirror mounted in the box 2 against the bottom of the latter, and 75 which is secured therein by a plate 16, having an observation opening 17 which registers with the mirror 15. Three edges of the plate 16 are respectively fastened to the adjacent inner walls of the box 2, said plate 80 being disposed against the mirror 15 parallel with the bottom of the box 2.

Projecting from the other edge of the plate 16, are two U-shaped arms 18, which 85 are preferably resilient, and which are adapted to receive between them and to releasably hold a comb, not shown, which may be inserted transversely in the box 2.

The box 1 at one side of the powder chamber may be provided with compartments 19 and 20 for receiving any desired articles, said compartments being normally covered by a hinged lid 21, which may carry a rouge box 22 and a plurality of coin holders 23, and also a paper holding clip 24.

90 The box 2 may be provided with any suitable catch 25 which is adapted to engage the box 1 to releasably hold the cover box 2 in the closed position. The box 1 at opposite sides and adjacent to one end may be provided with a suitable handle, such as a chain 26, Fig. 1.

100 In the operation of the device, when the case is closed and is in the position shown in Figs. 1 and 2, the powder puff 7 and the partition plate 5 hold the powder from sift- 105 ing out of the box.

When the case is to be used, the box 2

and cover 10 are swung to the open position, shown in Figs. 3 and 4, at which time the puff 7 may be removed for use, and access may be had to the different compartments in the case.

I do not limit my invention to the specific features shown and described, as many modifications, within the scope of the appended claim, may be made without departing from the spirit of my invention.

What I claim is:

In a vanity case, two boxes hinged to each other, one being adapted to form a cover for

the other, a mirror mounted in one of the boxes against the bottom thereof, and a plate disposed parallel with and against the mirror and having an observation opening registering with said mirror, and having at one edge two U-shaped arms adapted to receive between them and to hold releasably a comb, said plate being attached to the box in which it is located.

In testimony whereof I have signed my name to this specification.

CECILE E. CROSWHITE.
